Primary Examiner—Elizabeth A. Albert*Assistant Examiner*—Kelley A. Donnelly(74) *Attorney, Agent, or Firm*—Fredrikson & Byron, P.A.**CLAIM**

I claim the ornamental design for a swivel organizer, as shown and described.

DESCRIPTION

FIG. 1 is a perspective view of my new design for a swivel organizer;

FIG. 2 is a side perspective view thereof with both doors closed, the other side perspective view being a mirror image of that shown;

FIG. 3 is a side perspective view thereof with both doors open;

FIG. 4 is an opposite side perspective view thereof with both doors open;

FIG. 5 is a rear elevation view thereof, the front elevational view being a mirror image of that shown;

FIG. 6 is a side elevation view thereof, the other side elevation view is a mirror image of that shown;

FIG. 7 is top plan view thereof; and,

FIG. 8 is a bottom plan view thereof.
